UNITED STATES PATENT OFFICE

161,576

BEVERAGE MIXING SPINDLE

W. Arthur Ernst, Racine, Wis.

Application July 22, 1950, Serial No. 11,348

Term of patent 14 years

(Cl. D44—1)

To all whom it may concern:

Be it known that I, W. Arthur Ernst, a citizen of the United States, residing at Racine, in the county of Racine and State of Wisconsin, have invented a new, original, and ornamental Design for a Beverage Mixing Spindle, of which the following is a specification, reference being had to the accompanying drawing, forming part thereof.

Fig. 1 is a view in side elevation of a beverage mixing spindle embodying my new design.

Fig. 2 is a view taken in cross section on the line 2—2 of Fig. 1.

Fig. 3 is an inverted plan view of the beverage mixing spindle illustrated in Fig. 1.

Fig. 4 is a view taken in cross section on the line 4—4 of Fig. 1.

Fig. 5 is a view taken in cross section on the line 5—5 of Fig. 1.

Fig. 6 is a fragmentary detail view showing the mixing head in side elevation from a viewpoint forty-five degrees removed from that of Fig. 1.

I claim:

The ornamental design for a beverage mixing spindle, as shown.

W. ARTHUR ERNST.
